UNITED STATES PATENT OFFICE.

PHILIP G. HUBERT, OF LOS ANGELES, CALIFORNIA

COOKER.

No. 920,330.

Specification of Letters Patent.

Patented May 4, 1909.

Application filed December 20, 1907. Serial No. 407,285.

To all whom it may concern:

Be it known that I, PHILIP G. HUBERT, a citizen of the United States, residing at Los Angeles, in the county of Los Angeles, State of California, have invented new and useful Improvements in Cookers, of which the following is a specification.

My invention consists of a novel combination of a burner or other heating means with one or more of the devices commonly known as fireless cookers and it further consists in the novel construction of such fireless cookers for adaption to this combination.

The prime object of my invention is to provide a novel and efficient combination whereby the articles to be cooked may be initially heated by means of the stove and thoroughly cooked with the minimum amount of fuel or heating agent.

20 A further object is to provide a mechanism which is simple in operation and which easily lends itself to easy and rapid cooking.

A further object resides in the construction of the cooker so that it may absorb a 25 large quantity of heat to be utilized in the cooking of the articles placed therein.

I accomplish the above objects by means of the device described herein and illustrated in the accompanying drawings, in which:—

30 Figure 1,—is a front elevation of my improved cooker. Fig. 2,—is a vertical section of a portion of the same with the parts in their operative positions. Fig. 3,—is a sectional plan view taken on line 3—3 of Fig. 35 2. Fig. 4,—is a sectional detail of one of the weights and the mechanism therefor.

Referring to the drawings 5 designates a cabinet case which may be constructed as a 40 separate piece of furniture or it may be built into the wall of an apartment to form a fixture therein. As the cooker is conveniently supported at a working height from the floor the lower part of case 5 may be occupied by drawers 6 or any other utilities which may 45 be desired. Above the drawers the cabinet is preferably divided into two vertical runways 7 and 8 by a central partition 9 and cooker boxes 10 and 11 are adapted to slide vertically in runways 7 and 8, being held in 50 position by guides 12 mounted on central partition 9 and on side walls 13 of the cabinet. Counter balance weights 14 are connected to boxes 10 and 11 by cords 15 which pass over pulleys 16 and the weights are 55 sufficiently heavy to allow boxes 10 and 11 to be lifted with but a slight effort.

At the bottom of each of runways 7 and 8 is a burner 17 mounted in a preferably metallic box 18 which projects above the burner and supports a plate 19 above the same. I 60 have shown a cooker which is especially adapted for home or hotel use and have consequently constructed the same for both boiling and the like and for baking. To this end the cooker on the left is constructed of a 65 circular configuration and box 18 is therefore circular, while the cooker on the right is square as is box 18. The left hand or boiling cooker will be first described and the baking cooker afterward described in so far as 70 its construction differs from the boiling cooker.

Cooker box 10 is square as shown in Fig. 3 and is open at its lower end. A lining 20 of hair felt is provided immediately against the 75 outer walls of the box and immediately adjacent this lining is a filling 21 of sawdust or similar material which is packed tightly in place between lining 20 and an inner lining 22 of asbestos or other similar insulating material. Lining 22 is placed immediately around an inner circular wall or lining 23 which may be formed either of earthen ware or cast iron or in fact any material which will absorb a large quantity of heat. A facing 24 covers the bottom edge of the completed box and holds the constituent parts in proper relation to each other and also prevents filling 21 from escaping. When in its operative position as shown in Fig. 2 facing 90 24 rests upon a filling 25 of hair felt or other suitable material which is placed around box 18 in the cabinet and thus forms an air and heat tight joint between the cabinet and the cooker box. Asbestos or magnesium may 95 well be used in this position as they are non-combustible and are also non-conductors of heat.

In the operation of my improved cooker a receptacle 30 is placed on plate 19 with the 100 articles therein to be cooked and a fire is started at burner 17. This burner may be of any preferred type such as gas or gasoline and the fuel fed thereto through a supply pipe 31. Cooker box 10 is then lowered to a 105 position a short distance above the burner so that, although the receptacle is inclosed, sufficient space is afforded for the burner to be thoroughly ventilated while the fire is burning. The fire is continued until receptacle 30 and its contents are thoroughly heated and until inner wall or lining 23 has 110

absorbed its maximum amount of heat. Lining 23 is constructed for this particular purpose of a material which will quickly absorb a large amount of heat and slowly radiate the same. After the fire has been shut off cooker box 10 is lowered into its operative position as shown in Fig. 2 and the articles to be cooked together with heated lining 23 are thereby inclosed by non-conducting walls which hold their heat for a long period of time. Lining 23 having stored up a large amount of heat this heat is gradually given off and passes into the articles which are being cooked. Thus the temperature of the cooker is maintained for a long period of time and the articles therein are thoroughly cooked without any danger of overheating.

The right hand or baking cooker differs slightly in construction from the boiling cooker in order to adapt it to baking. To this end cooker box 11 is provided with an inner lining 35 corresponding to inner lining 23 of cooker box 10, lining 35 however being square in configuration so that an oven 36 of usual construction may be placed within the cooker. The operation of this cooker is precisely the same as the one just described, oven 36 taking the place of inner lining 23 in absorbing and holding a large amount of heat to be subsequently radiated into the articles which are being baked.

As illustrated in Fig. 1 I have provided cabinet 5 of sufficient height to enable cooker boxes 10 and 11 to be raised above the burners a convenient distance so that the ordinary operations may be carried on underneath them. In this figure I have shown cooker box 10 as being in its elevated position and cooker box 11 as in its lowered or operative position. Handles 37 are provided for the manipulation of the boxes and weights 14 are just sufficiently heavy to allow the boxes to be placed in and to remain in any position.

In Fig. 4 I have shown in detail the arrangement for relieving weights 14 from the cooker boxes so that the same may rest with their full weight upon the cooker bases and thereby form a tight joint to prevent the escape of heat from the cooker. To this end weights 14 are comprised of frames 40 which are adapted to receive bricks 41 or other suitable objects, these frames being suspended from the rear ends of cords 15 in a compartment 42 in cabinet 5. Directly above each of frames 40 I have provided on cabinet 5 a pivoted lever 43 from whose rear

end a hook 44 depends and is adapted to hook under the top of frame 40. Upon the downward movement of lever 43 at its forward end weight 14 is raised and cord 15 is thereby loosened as shown in Fig. 1, a hook 45 being hooked over the forward end of lever 43 and holding the same in position. When it is desired to release the weights so as to raise the cooker box, hook 44 is released from engagement with frame 40 by means of a cord 46 which is attached to the upwardly projecting end 47 of hook 44 and which is arranged in a convenient position to be operated from the front of the cooker.

From the foregoing description it will be observed that I have provided a novel combination of a burner and a fireless cooker whereby the ordinary operations of cooking may be conveniently and efficiently carried out. It will further be noted that in the construction of the cooking boxes I have provided a means whereby the temperature of the articles placed within the same may be maintained at a high point for a sufficient length of time to thoroughly cook any article of food.

Having described my invention what I claim as new and desire to secure Letters Patent is:—

1. A cooker comprising a casing provided with a vertical runway, a heating means at the bottom thereof, a cooker box slideable in said runway and adapted to rest over said heating means; a counter-balance for said box, and means for guiding the movement of said box.

2. A cooker comprising a casing provided with a vertical runway, a heating means at the bottom thereof, a cooker box slideable in said runway and adapted to rest over said heating means, a counter-balance for said box, and means for relieving the box from the operation of the counter-balance when the box is in lowered position.

3. In a device of the kind described, a cooker box, a counter-balance, a hook adapted to engage said counter-balance, a lever to which said hook is attached, a retaining hook for said lever, and means for tripping said first named hook.

In witness that I claim the foregoing I have hereunto subscribed my name this 11th day of December, 1907.

PHILIP G. HUBERT.
